(57) **CLAIM**

I claim the ornamental design for the inflatable stadium or bleacher seat, as shown.

DESCRIPTION

FIG. 1 is a perspective view of the inflatable stadium or bleacher seat;

FIG. 2 is a side elevation view thereof;

FIG. 3 is a front view thereof;

FIG. 4 is a top view thereof;

FIG. 5 is a back view thereof; and,

FIG. 6 is a bottom view thereof.

The cross-hatching pattern shown in the drawing is understood to be repeated uniformly throughout the circumscribed area.
